UNITED STATES PATENT OFFICE.

TELESPHORE BABIN, OF HOUma, LOUISIANA.

ACETYLENE-GAS GENERATOR.

1,225,559.

Specification of Letters Patent.

Patented May 8, 1917.

Application filed December 12, 1912. Serial No. 736,383.

To all whom it may concern:

Be it known that I, TELESPHORE BABIN, a citizen of the United States, residing at Houma, in the parish of Terrebonne and State of Louisiana, have invented a new and useful Acetylene-Gas Generator; and I do hereby declare the following to be a full, clear, and exact description of the invention, such as will enable others skilled in the art to which it appertains to make and use the same.

This invention relates to a new and useful acetylene gas generator.

As one of the objects of the invention, it is the aim to improve the structure of the acetylene gas generator, shown, set forth, and claimed in the Patent No. 843,429.

Another object of the invention is to provide an apparatus of this nature, simple, efficient, and practical in construction, and one which may be easily operated.

The invention comprises further features and combination of parts, as hereinafter set forth, shown in the drawings and claimed.

25 In the drawings:—

Figure 1 is a view in side elevation of the improved acetylene gas generator constructed in accordance with the invention.

Fig. 2 is a vertical sectional view through the generator.

Fig. 3 is a sectional view on line 3—3 of Fig. 1.

Fig. 4 is a sectional view on line 4—4 of Fig. 1.

Fig. 5 is a sectional view on line 5—5 of Fig. 1.

Fig. 6 is a detail view.

Referring more particularly to the drawings 1 designates the gas generator tank, 20 while 2 denotes the gas reservoir, which includes the gasometer bell 3. Arranged in the gas generator tank is a bell 4, under which and above the water the gas is generated. This bell 4 terminates at its upper portion in a supplemental casing 5, forming a carbid chamber 6, which is provided with a conical bottom 7. The casing 5 is provided with an opening 8, through which the carbid may be introduced into the chamber 6.

45 This opening 8 is closed by a threaded plug 9. The conical bottom 7 of the carbid chamber is provided with an opening 10 at its apex, which is normally held closed by the valve or closure 11. This valve or closure is 55 constructed upon the upper end of a rod 12.

The lower end of the rod has a plate 13 secured to it.

The pipe 14 has its upper and lower ends open, and when the gas in the bell decreases, the bell lowers and the lower end of the pipe 60 14 extends into the water, thereby sealing the lower end of said pipe. However, when the gas increases in the bell 4, the bell rises, and should the gas increase enough to raise the bell sufficiently to cause the lower end of 65 the pipe 14 to assume a position above the level of the water, the excessive gas will escape through said pipe 14. Passing through pipe 15 is a rod 16 terminating in a laterally extending portion 17, which in turn 70 is provided with a forked end 18, in which the lower flat end plate 13 is secured by the pin 18^a. The flat plate on its opposite flat surfaces fits exceedingly close between the forks 18, as shown in Fig. 3, while the edge 75 18^b of the plate 13 engages the crotch 13^a exceedingly close as shown in Fig. 2, so as to support the rod 12 with rigidity at right angles to the portion 17. To start the generation of gas, the rod 16 is shaken or twisted, 80 which will, owing to its laterally extending portion at its lower end, rock the closure or valve in the carbid chamber, thereby allowing a few grains or particles of carbid to fall in the water of the tank 1, after which, 85 by raising the rod 16 slightly, the closure or valve may be slightly opened, in order to allow a further charge of carbid to fall in the water. As the carbid falls in the water, gas is generated, which causes the bell 4 to 90 ascend. As the gas is generated, it escapes from the bell 4 through the pipe 20. As the gas leaves the bell 4, the bell 4 gradually lowers. Threaded upon the upper portion 95 of the rod 16 is a nut 21, adapted to engage the other end of the pipe 15, in order to support the rod 16, thereby holding the valve or closure in the carbid chamber in an open position. By screwing the nut 21 downwardly or upwardly, the closure or valve of the carbid chamber may be held in different positions. Secured to the pipe 15 upon the exterior of the bell 4 is a sleeve 22 having a laterally extending ear 23, in which a link 100 24 is pivoted.

The acetylene gas generator when not operating has its valve 11 closed, the nut 21 of the rod 16 is screwed tight against the upper end of the pipe 15, and is held against said pipe by inserting the hook 26 of the 110

tubular rod 25 (which is adjustably threaded to the link 24) into the aperture 27 of the rod 16, thereby holding the nut 21 jammed against the upper end of the pipe 15. When the generator is to be operated, the hook 26 is removed from the aperture 27, after which the nut 21 is adjusted, so that the rod 16 will rise telescopically through the pipe 15, in which case the valve 11 will open, as shown in Fig. 2, owing to the valve rod 12 being pivoted to the lower end of the rod 16. After so opening the valve 11, the tubular rod 25 may be adjusted upwardly, so that the hook 26 will register with and enter the aperture 27, thereby holding the valve so opened. Said valve may be opened to any desired position. When the valve is to be closed, the nut 21, after disconnecting the hook 26, is so turned or rotated, that the rod 16 will lower, in which case the valve 11 will correspondingly lower and become closed, in which case, the hook 26 may be returned in engagement with the aperture 27. In order to prevent the rod 16 from being further raised, the tubular rod 25 may be extended by unscrewing the same with relation to the link 24, sufficiently to allow the hook 26 to enter the aperture 27. An additional pipe 29 is arranged on the interior of the bell 4, and terminates upon the exterior. Extending through the pipe 29 is a rod 30, to the upper end of which a laterally extending lever 31 is pivoted, while to the lower end a scraper blade 32 extending laterally, is pivoted. By rocking the rod 30 by manipulating the lever 31, the scraper blade will dislodge the sediment in the bottom of the tank 1, and by removing the plug 33 (which is threaded in the tank 1 adjacent its bottom), the sediment and the like may be drawn off from the tank 1. The tank 1 may be supplied with water, through the spout 34, there being perforations in the side of the tank to allow the water to enter. The gas pipe 20 threads into an elbow 35, which in turn is threaded to the union 36. This union 36 threads into an elbow 37 on the exterior of the tank 1, there being flange members 38 threaded or otherwise secured, one upon the interior and one upon the exterior of the tank 1. In this manner a water tight connection is provided. Threaded to the elbow 37 is a drain valve 39, serving to permit drainage of any water that may accumulate in the pipes 20, 36 and 42. The elbow 37 is connected to the valve casing 40 (in which a valve 41 is arranged) by virtue of the union 42. The valve casing 40 is in turn connected to a short length of pipe 43, between which and a similar pipe 44 a union 45 is connected. This union 45 comprises the parts 46 and 47 held together by the member 48, which is threaded to the part 47. The pipe 44 is threaded into an elbow 49 on the exterior of the tank 2. This elbow 49 is connected to a union 50, which in turn threads into the elbow 51 on the interior of the tank 2, there being flange members 52 and 53 threaded into the wall of the tank 2, one upon the exterior and one on the interior. Threaded to and rising from the elbow 51 upon the interior of the bell 3 is a gas pipe 54, which terminates at its upper portion in an overhanging goose neck 55, which comprises the elbows 56 and 57, the nipple 58 and the extension pipe 59. This gas pipe 54 conveys the gas into the reservoir tank 2, and under the gasometer bell 3 of the tank 2. The gas under the gasometer bell is carried off by way of the pipe 60, which is secured to the tank 2 of the gas reservoir, in a manner similar to the connection of the gas pipe in the tank 1. A T-union 62 with which the pipe 60 connects, as shown, is provided with a drain valve 63, in order to drain the gasometer bell of the excess gas, especially when a certain number of burners or jets or the like (not shown) which are adapted to be connected to the gas discharge pipe 65 are cut off, prior to regulating the carbide from the carbide chamber or container. The tank 2 is supplied with water, by way of the pipe 66. Threaded to a union 67 on the exterior of the tank 2 is an elbow 68 having a pipe extension 69. This elbow 68 may be rocked downwardly or upwardly, and is adapted to carry off the overflow of water in the tank 2. In other words, by arranging the extension pipe 69 substantially horizontally, the water in the tank 2 will not rise any farther than the nipple 67, for the water will be carried off by way of the extension pipe 69, as well as by the union 67. By arranging the extension pipe 69 at an angle toward an upper vertical position, or exactly to an upward vertical position, the water in the tank 2 may be increased in its height. In order to regulate the supply of water to the tank 2, the pipe 66 is provided with a valve of the usual construction, designated by the numeral 70. The upper portion of the gasometer bell 3 is provided with a handle 71, whereby the bell may be manually raised or lowered. Forming a part of the handle 71 is an eye 72, in which the angled end 73 of a rod 74 is arranged. This rod 74 is in turn pivotally connected at 75 to a rod 76, which in turn is connected at 77 to the valve 41. It will be seen that by this connection between the gasometer bell and the valve 41, communication between the gas pipe 20 of the gas tank 1 and the gas pipe 54 of the tank 2, is automatically controlled, as the gasometer bell 3 rises and falls. In other words the normal position of the gasometer bell 3 is downwardly and as the gas is generated in the tank 1, the same is carried off by way

of the pipe 20, through the passage-way between the two tanks, and under the gasometer bell, by way of the gas pipe 54. As the gas accumulates under the gasometer bell, the same ascends, and when it reaches a certain position during its ascension, communication between the two tanks 1 and 2 is automatically cut off, by virtue of the valve 41. As the gas under the bell is consumed, the bell lowers or descends, which also tends to force the gas out through the pipe 60.

In using this form of acetylene gas generator, the valve 11 is set or opened just sufficiently to allow a requisite quantity of carbid to fall or feed into the water, so as to maintain just a trifle more of gas in the gasometer bell 4 than enough to supply a certain number of jets, and as the gas is cut off at one, two or three jets, said valve is re-regulated, hence the provision of the means, whereby the valve may be adjusted the slightest degree and held so adjusted. When the gas is cut off from all the jets, the flow of the carbid is cut off, therefore the generation of gas ceases. For instance, if there are ten jets to be supplied with gas, for a period of ten to fifteen hours, then the valve 11 is set, in order to feed a requisite amount of carbid, in order to generate just a trifle more of gas, than is required for the ten jets. Therefore, for ten to fifteen hours the acetylene generator would not require a constant attendant.

The operation of the generator is as follows:

The tanks 1 and 2 are filled with water in the usual manner to the desired height. The bells 3 and 4 are placed in their respective tanks, and the carbid chamber 6 filled with carbid through the opening 8, first having removed the plug 9. By raising the rod 16 a mere trifle, the valve 11 will be unseated, owing to the valve being connected to the rod 16. After the rod 16 has been so raised the nut 21 is set, as shown in Fig. 2, preventing the rod from descending. Then by adjusting the tubular rod 25 relative to the link 24, the two of them being threaded together, the hook 26 is placed in engagement with the aperture 27 at the upper end of the rod 16. In this manner the valve 11 is held slightly opened, thereby permitting a flow of carbid into the water of the tank 1, which water, owing to the pipe 14 opening to the outside atmosphere enters up into the bell 4. The gas is generated in the bell 4 and passes down through the pipe 20 and through the connections (which includes the valve 41) into the gasometer bell 3 by way of the pipe 54 and the goose neck 55. Since the pipe 60 (which extends up into the bell 3) is connected to the service or discharge pipe 65, the gas may be carried off to be consumed for any suitable purpose

such as lighting. If there is an excessive amount of gas in the bell 3 the same may be drained by virtue of the valve 63. Also if there is an excessive quantity of gas in the bell 4 it may also be drained by virtue of the valve 39. As the gas is generated and passes into the bell 3 in excess to the consumption or utilization of the gas by way of the service pipe, the bell 3 will ascend sufficiently in order to close the valve 41, owing to the connections 72, 73, 74 and 75, and 76 and 77 between the valve 41 and the bell 3, thereby cutting off the gas from passing from the bell 4 to the bell 3, which will cause the bell 3 to lower, which will re-open the valve 41. As in the operation of all acetylene gas generators an attendant is to be in charge of the present form of apparatus, and in this case, when the consumption of gas is less than the generation of the same, which will cause the bell 4 to rise to such a position that the lower end of the pipe 14 will be above the level of the water in the tank 1, thereby causing the escape of gas into the room in which the generator is contained, the duty of the attendant is to close the valve 11, by adjusting the nut 21 and the tubular rod 25 accordingly, to not only close the valve 11, but to hold the same closed, thereby cutting off the flow of the carbid. Another way for obviating the escape of the gas into the room is to provide some suitable connection (not shown) between the valve 39 and the outdoor atmosphere, in order to drain the bell of the excess gas. The sludge or sediment that may accumulate in the bottom of the tank 1 may be stirred by the device 32, by operating the handle 31. The invention having been set forth, what is claimed as new and useful is:—

In combination with a bell casing of a gas generator to rise and fall incident to the increase and decrease of gas therein, said casing having a chamber containing gas generating material in its upper end provided with a conical bottom terminating in an opening, said casing having a guide pipe, a rod mounted in said guide pipe and having at its lower end a right angle extending portion, a second rod pivoted to said right angle extending portion and extending through the opening of the conical bottom, and provided with a valve to open and close said opening to control the flow of the gas generating material through said opening, the first rod having its upper end threaded and provided with an aperture at its extremity, a nut engaging the threads of the first rod and to coöperate with the upper end of the guide pipe to lift and assist in holding the first rod in different adjusted positions, said casing having an apertured member, a link pivoted in the aperture of said member, and a tubular rod

threaded to said link and having at its upper end a hook to engage the aperture at the upper end of the first rod, to hold the nut in contact with said guide pipe, to secure the valve in different adjusted opened positions.

In testimony whereof I have signed my

name to this specification in the presence of two subscribing witnesses.

TELESPHORE BABIN.
